UNITED STATES PATENT OFFICE.

MORTON HAVENS, JR., OF ALBANY, AND SAMUEL B. VAN RANST, OF SYRACUSE, NEW YORK; SAID VAN RANST ASSIGNOR TO CROUSE-HINDS COMPANY, OF SYRACUSE, NEW YORK, A CORPORATION OF NEW YORK.

BRANCH BOX FOR ELECTRIC CONDUCTORS.

1,195,813.

Specification of Letters Patent. Patented Aug. 22, 1916.

Application filed January 27, 1909. Serial No. 474,469.

To all whom it may concern:

Be it known that we, MORTON HAVENS, Jr., of Albany, in the county of Albany and State of New York, and SAMUEL B. VAN RANST, of Syracuse, in the county of Onondaga and State of New York, have invented a certain new and useful Branch Box for Electric Conductors, of which the following is a specification.

10 This invention relates to novel means for inclosing portions of electric circuits at or contiguous to the junction of branches thereof, and consists in the the combinations and constructions hereinafter set forth and 15 claimed.

In describing this invention, reference is had to the accompanying drawings, in which like characters designate corresponding parts in all the views.

20 Figure 1 is a sectional view, partly in elevation, of one embodiment of our invention. Fig. 2 is a plan of the detached body of the device. Fig. 3 is a detail section on line 3—3, Fig. 2. Fig. 4 is a perspective view 25 of the insulating means or ring.

In the embodiment of the invention disclosed, a hollow body 1 is employed which is preferably a single piece of cast metal of cylindrical form and comprises a rear side 30 2, an outer side wall 3, one or more conduit couplings 4, and a front side or top 5. The rear side 2 is preferably substantially flat, is secured by any suitable means, as screws 6, to any desirable base 7, as a ceiling, and is 35 provided with a substantially central opening 8 extending therethrough from front to rear and adapted to receive and loosely fit an electric conducting supporting part 9, as a gas pipe, or other lighting fixture 40 standard, here shown as fixed relatively to the base 7, as arranged at an angle thereto and as comprising front and rear sections insulated from each other by an insulating member or coupling 10 of any desirable 45 form, size and construction.

Preferably, the body 1 is provided at its central portion with a part 11 which constitutes an internal wall for the body 1, is spaced apart from the outer side wall 3, 50 and incloses a passage 12 forming a continuation of the opening 8 and serving to receive the contiguous portion of the part 9. This part or internal wall 11 is mounted on the rear side 2, is terminated at the rear

of the front face of the side 5, and is provided with movable means for making electrical contact with the part 9, such means being here shown as a screw 13 movable endwise into the passage 12 at an angle to the axis of said passage. We have here 60 shown the part 11 as detachably secured to the rear side 2 by suitable means, as screws 14, but to those skilled in the art, it will be apparent that said part may be formed integral with the rear side, or if desired, 65 may be entirely dispensed with, and that in lieu thereof, other means may be used for electrically connecting the body 1 to the supporting part 9.

The conduit couplings 4 are shown as 70 consisting of interiorly threaded nipples projecting from the side wall 3 substantially radially of the body 1, and serving to connect to the space between the outer and inner walls 3 and 11 of the body 1, one or more 75 conduits 15 adapted to contain electric conductors 16, and suitably fixed relatively to the base 7 by any desirable means, as loops 17. Preferably, the couplings or nipples 4 are of a diameter greater than the thickness 80 of the body 1, their rear sides being disposed in substantially the same plane as the rear side of the body 1, and their front sides projecting beyond the front side of the body. It is apparent, however, that this invention is not limited to conduit couplings 85 consisting of interiorly threaded nipples projecting from the side wall 3, and that any other suitable means may be used for connecting one or more conduits to the interior of the body 1.

The front side 5 of the body 1 is provided with a substantially central opening 18 extending therethrough from front to rear substantially in line with the opening 8 and 95 the passage 12 and also receiving the part 9, this opening 18 being preferably of larger diameter than the opening 8. Said openings 8 and 18 and the passage 12 thus constitute a passage extending through the 100 body 1 from front to rear thereof, for permitting said body to encircle the supporting part 9, and the opening 18 permits the egress of branches of the electric conductors 16 from the body 1 alongside the supporting 105 part 9. Said front side 5 also includes a ring shaped flange 19 projecting from the outer portion of the side wall 3, and over-

hanging the rear side 2, such flange having a front substantially flat face 20 concentric with the opening 18 and preferably depressed or disposed at the rear of the front sides of the conduit couplings 4, said flange having an outer supporting surface for fixture members as canopies which surface is disposed throughout its entire extent in a plane substantially parallel with the outer face of the bottom.

Preferably, the branch electric conductors passing through the opening 18 alongside of the supporting part 9 are concealed by means, as a shell 21, encircling the supporting part 9 in front of the hollow body 1, and having the portion thereof opposed to said body formed of greater diameter than the opening 18 and arranged substantially concentric with said opening. This shell 21 may be held in place by any suitable means, as a collar 22 on a sleeve 23, carried by the supporting part 9 and projecting within the shell 21. The body 1 and the shell 21 are preferably insulated from each other by suitable means, as a ring 24 having one side resting against the bearing face 20 of the front side 5, and its other side formed with a groove for receiving the opposing edge of the shell 21. This ring 24 is formed relatively thin, so that its front face is approximately in line with the front faces of the couplings 4.

As will be apparent to those skilled in the art, our invention provides substantial, durable, compact and sightly means for connecting conduits to a ground, and for permitting the egress of branches from electric conductors within the conduits, and concealing said conductors and branches at or contiguous to the junctions thereof.

What we claim is:—

1. An electrical conduit outlet box comprising a flat bottom adapted to lie against a base or wall, said bottom having a central opening for receiving a fixture-supporting pipe passed axially through the outlet box, a side wall rising from the outer edge of the flat bottom and provided with one or more laterally projecting nipples for detachable connection with electric conduits, and a top wall depressed beneath the plane of the tops of said nipples and formed with a central opening of greater size than the first-mentioned opening for permitting the passage of said pipe and access to the interior of the fitting around the pipe, said top wall including a ring-shaped flange around the central opening having an outer supporting face for fixture-members as canopies and the like, said face being disposed throughout its entire extent in a plane substantially parallel with the outer face of the flat bottom.

2. An electrical conduit outlet box comprising a flat bottom adapted to lie against a base or wall, said bottom having a central

opening for receiving a fixture-supporting pipe passed axially through the outlet box, a side wall rising from the outer edge of the flat bottom and provided with one or more laterally projecting nipples for detachable connection with electric conduits, and a top wall depressed beneath the plane of the tops of said nipples and formed with a central opening of greater size than the first-mentioned opening for permitting the passage of said pipe and access to the interior of the fitting around the pipe, said top wall including a ring-shaped flange around the central opening having an outer supporting face for fixture-members as canopies and the like, said face being disposed throughout its entire extent in a plane substantially parallel with the outer face of the flat bottom, and the inner ends of the top portions of the nipples being formed with depressed flat surfaces disposed substantially in the plane of said outer face of the top wall.

3. An electrical conduit outlet box comprising a flat bottom adapted to lie against a base or wall, said bottom having a central opening for receiving a fixture-supporting pipe passed axially through the outlet box, and said bottom having around its central opening a series of holes for the passage of means for securing the conduit outlet box to said base or wall, a side wall rising from the outer edge of the flat bottom and provided with one or more laterally projecting nipples for detachable connection with electrical conduits, and a top wall depressed beneath the plane of the tops of said nipples and formed with a central opening of greater size than the first-mentioned opening for permitting the passage of said pipe and access to said securing means and to the interior of the fitting around the pipe, said top wall including a ring-shaped flange around the central opening having an outer supporting face for fixture-members as canopies and the like, said face being disposed throughout its entire extent in a plane substantially parallel with the outer face of the flat bottom.

4. An electrical conduit outlet box comprising a flat bottom adapted to lie against a base or wall, said bottom having a central opening for receiving a fixture-supporting pipe passed axially through the outlet box, a cylindrical side wall rising from the outer edge of the flat bottom and provided with one or more radially projecting nipples for detachable connection with electrical conduits, and a top wall depressed beneath the plane of the tops of said nipples and formed with a central opening of greater size than the first-mentioned opening for permitting the passage of said pipe and access to the interior of the fitting around the pipe, said top wall including a ring-shaped flange around the central opening having an outer sup-

porting face for fixture-members as canopies and the like, said face being disposed throughout its entire extent in a plane substantially parallel with the outer face of the 5 flat bottom, and the inner ends of the top portions of the nipples being formed with depressed flat surfaces disposed substantially in the plane of said outer face of the top wall, substantially as described.

10 In testimony whereof I, your petitioner, MORTON HAVENS, Jr., have hereunto signed my name in the presence of two attesting witnesses at Albany, in the county of Albany, in the State of New York, this 15th day of 15 January, 1909, and I, your petitioner,

SAMUEL B. VAN RANST, have hereunto signed my name in the presence of two attesting witnesses at Saranac Lake, in the county of Franklin, in the State of New York, this 6th day of January, 1909.

MORTON HAVENS, JR.

SAMUEL B. VAN RANST.
